ROTARY PUMP

David Wittenberg, Romema, Jerusalem,
PalestineApplication September 1, 1944, Serial No. 552,227
In Palestine August 31, 1943

2 Claims. (Cl. 103—149)

1

The invention has for its object to provide a new type of rotary pumps which is distinguished from the known pumps by its simplicity of construction and operation, and consists in principle in a pump comprising a resilient tube bent into a helical coil and a rotary pressure member, such as an eccentric disc, rolling over and progressively compressing the tube. By this means the liquid or gas contained in the tube in front of the rotating roller or eccentric disc is pressed in the direction of rotation, and at the same time the tube portions behind the rotating member reassume, owing to their resiliency, their original shape and volume and suck in fresh fluid. The fluid flows without interruption and no check valve need to be provided to prevent any reflux, since the tube is always compressed at one point.

The new pump offers several important advantages. There is no piston or rotor moving within the liquid pumped, it has the appearance of the known rotary pump, but has no stuffing boxes for a piston rod or rotor shaft and corrosive liquids or gases can be easily handled without any protective coating hitherto used for the piston or rotor.

The invention is illustrated in the annexed drawing, wherein,

Fig. 1 is an elevational view of the pump;

Fig. 2 is a vertical section on the line II—II of Fig. 1.

Fig. 3 and Fig. 4 show constructional details on a larger scale.

The new pump comprises a rubber tube 1 bent into a coil with preferably slightly more than one turn only. The coil is accommodated in an iron cylinder 2 with cast short intake and outlet pipes 3, 4. The coil is held in the cylinder by projecting with its ends into the pipes 3, 4. Cylinder 2 is closed at one end by a screwed on cover 5, and is attached at the other end to the flange 6 of a shaft bearing 7 forming part of a pedestal 8. In the bearing 7 is journalled a shaft 9 projecting with one end into the tube coil, where it has keyed thereto an eccentric disc 10. The outer end of shaft 9 may be coupled to an electromotor or transmission.

To reduce the friction otherwise occurring between the rotating eccentric and the tube, a metallic ring 11 is arranged on the circumference of the eccentric which rolls upon the flattened tube while the eccentric rotates within the ring. The metallic ring 11 fits tightly into the inner space of the coil so that the wear of the

2

pipe by the rotation of the eccentric is completely eliminated. The width of the ring is approximately the same as that of the cylinder 2.

For further reducing the friction between the ring 11 and the tube-coil, the ring 11 is provided with a pin 12 engaging into a slot of a bar 13 pivoted by means of another pin 14 to an eye 15 of the casing 2. While the eccentric is rotating pin 12 slides in the slot and the bar 13 oscillates about its pivot and prevents ring 11 from rotating. Thus no relative movement takes place between the contacting surfaces of the ring 11 and the tube. Tube 1 may be provided with projections or buttons 16 fitting into corresponding depressions of the ring 11, thus wholly preventing any relative movement between the ring and the tube.

It would be within the scope of the present invention, if instead of the eccentric disc a crank arm would be fixed on the shaft 9 and the free end of this arm provided with a roller travelling on and compressing the tube.

What I claim is:

1. A rotary pump, comprising a resilient tube bent into a helical coil, having more than one full turn, a cylindrical casing in which this coil is fixed, an eccentric disk rotatable within the coil, and a metallic ring inserted between the eccentric and the coil, the coil being provided with projections fitting into recesses of the ring, said eccentric disk being adapted, by means of said ring, to compress said tube progressively and continuously through an angle of 360° with elimination, by said ring, of friction between said disk and tube.

2. A rotary pump comprising a resilient tube of circular cross section, bent into a helical coil having slightly more than one full turn and having side lines parallel to its axis throughout its length, a cylindrical casing, in which this coil is fixed, an eccentric disk rotatable within the coil, and a metallic ring inserted between the eccentric and the coil, a pin provided on said casing, a bar pivoted on said pin, said bar having a slot, a second pin on said ring, said second pin engaging into said slot and thereby holding said ring against rotation, said eccentric disk being adapted, by means of said ring, to compress said tube progressively and continuously through an angle of 360° with elimination, by said ring, of friction between said disk and said tube.
